UNITED STATES PATENT OFFICE.

CHARLES BUTCHER, OF CAMBRIDGE, MASSACHUSETTS.

POST-HOLE DIGGER.

No. 827,682.

Specification of Letters Patent.

Patented July 31, 1906.

Application filed February 23, 1906. Serial No. 302,411.

To all whom it may concern:

Be it known that I, CHARLES BUTCHER, a citizen of the United States, residing at Cambridge, in the county of Middlesex and State 5 of Massachusetts, have invented new and useful Improvements in Post-Hole Diggers, of which the following is a specification.

This invention relates to improvements in devices for excavating earth, commonly 10 known as "post-hole diggers."

It relates more particularly to the type of instrument shown in United States patents granted to me March 15, 1904, No. 754,421, and September 12, 1905, No. 799,445. In 15 this instrument the scoop or blade is pivoted to the lower end of the handle and adapted to be swung from substantially a vertical downward digging position to a horizontal earth-removing position while still inserted 20 in the earth, whereby the earth may be removed from a vertical hole of small diameter.

The objects of the improvement are to improve the mechanism and increase the facility and convenience of operation and to render 25 the instrument automatic in certain respects. These objects are attained by the means illustrated in the accompanying drawings, in which—

Figure 1 is a front elevation of one form of 30 the device, showing it ready for digging. Fig. 2 is a central longitudinal section on the line 2 2 of Fig. 1. Fig. 3 is a side elevation showing the blade in position for removal of earth vertically. Fig. 4 is a partial rear view 35 of the upper part of the handle. Fig. 5 is a cross-section on the line 5 5 of Fig. 3. Fig. 6 is an enlarged longitudinal section of a detail.

Similar letters refer to similar parts wherever they occur in the drawings.

Referring to the drawings, A represents the handle, to the lower end of which is pivoted a blade B of any desired form or size. A bar C lies longitudinally on the handle and is 45 movable longitudinally thereon within a casing D. It is attached at its lower end C' to a rod E, which is connected to the sides of the blade in any suitable manner. In the form illustrated this rod starts with a hook E' on one side of the blade, passes to its connection C' with the bar C, and then passes down to the other side of the blade, where there is a similar hook E'. Obviously when 50 the blade is turned downward upon its pivot this rod and its connected bar C will be drawn

downward upon the handle. A post A' is set in the handle to limit the downward motion of the bar. This post is T-shaped, the stock of the post being placed centrally in the path of the moving bar C and the cross-arms projecting sidewise across the rod E, thus binding it loosely to the handle and serving as a guide and guard to hold the rod E and lower end of bar C in their proper positions close to the handle A. As the strain 60 upon these parts when earth is being lifted from the hole tends to draw them outward away from the handle, this T-guide serves an important function in strengthening this part of the mechanism and relieves the casing D 65 of the strain, thus enabling the latter to be made of lighter material, which is more easily worked or formed into shape and makes less weight to handle when using the instrument.

The bar C is provided with a rack, and there is a pawl F set in the handle, the two being so shaped as to permit upward movement of the bar, but not downward movement. The pawl is operated by a lever H, which engages a neck formed in the outer end 70 of the pawl, and by this lever the pawl is moved into engagement or out of engagement. In my previous patent this pawl was shown as engaged directly by a spring, which was formed with a fork embracing said neck. 75 One feature of the present invention is an improvement on that in which the spring G is not attached directly to the pawl, but acts upon the lever and produces its effect upon the pawl only through the medium of the lever. 80 By this construction it is not necessary to cut any metal from the spring, and thus the spring may retain its full strength and the danger of breakage in cutting the spring is 85 obviated. The danger of breakage during 90 operation is also minimized. Another pawl S is arranged on the handle adapted to engage a shoulder on rack-bar C, which shoulder may conveniently be the upper end of the bar, as shown in Fig. 2, to prevent upward motion 95 of said rack-bar. This pawl constitutes a latch, which may be operated solely through the medium of a lever Q, similar to the lever H, and a spring R is arranged in contact with the lever Q to press the pawl normally toward its position of engagement through the medium of said lever. This pawl is so located with respect to the end of the rack-bar 100 that it will engage the same automatically whenever the latter is dropped to its lowest 105 110

position (shown in Fig. 2) and only then, its face being beveled, so that it rides harmlessly over the rack when the bar is in raised position. Its locked position corresponds to 5 the downward position of the blade into which the same is adjusted when it is to be used for digging. Upon dropping the blade to this position the pawl automatically locks it there and the workman uses the device as a 10 stiff-bladed shovel until he is ready to change the same to a scoop, when he presses upon the releasing-lever Q and begins to rock the handle backward and forward. This causes the blade to gradually work into the horizontal 15 position shown in Fig. 3. The rack-bar meanwhile works gradually upward during the oscillating movement from the position shown in Figs. 1 and 2 to that of Fig. 3. During this operation the pawl S produces no 20 effect, and the pawl F is in operation, engaging the rack-bar at each successive notch as the same works upward. Then the operator lifts the instrument from the excavation, bearing loose earth on the blade, which has 25 thus become horizontal. After discharging the earth from the blade pressure upon the lever H releases the rack-bar, the blade falls and becomes automatically locked in its downward position. By reason of the automatic 30 feature no reliance need be placed on the memory of the operator, and considerable time may be saved by making certain that the blade is in digging position each time it is introduced into the hole, thus preventing it 35 from changing its angle while being manipulated in the earth until the operator attends to releasing it.

I claim—

1. In combination with a handle and a blade pivotally connected thereto, a rod connected to the blade and guided longitudinally on the handle; and a T-post set in the handle constituting a stop and a guide for the rod. 40
2. In combination with a handle and a blade pivotally connected thereto, a movable bar connected to the blade and guided on the handle; means to latch the bar against motion in one direction; a lever controlling said latch; and a spring arranged to operate the latch through the medium of the lever. 45
3. In combination with a handle and a blade pivotally connected thereto, a bar connected to the blade and guided on said handle; and an automatic latch on the handle, arranged to engage the bar when in its downward position and thus lock the blade rigid. 50
4. In a post-hole digger, the combination, with a handle and a blade pivoted at one end of the handle, of a bar connected with the blade and movable longitudinally on the handle; means automatically engaging the bar when in its lowest position to prevent upward motion thereof; means automatically engaging the bar when not in its lowest position to prevent downward motion thereof; and 60 means for manually releasing each of said automatic engaging means. 65

In testimony whereof I affix my signature in presence of two subscribing witnesses.

CHARLES BUTCHER.
